PATENTED APR. 19, 1904.

W. L. ADAMSON.

MEANS FOR STOPPING RAILWAY TRAINS AT DANGER SIGNALS.

APPLICATION FILED JUNE 8, 1903.

NO MODEL.

UNITED STATES PATENT OFFICE.

WILLIAM L. ADAMSON, OF PHILADELPHIA, PENNSYLVANIA.

MEANS FOR STOPPING RAILWAY-TRAINS AT DANGER-SIGNALS.

SPECIFICATION forming part of Letters Patent No. 757,711, dated April 19, 1904.

Application filed June 8, 1903. Serial No. 160,553. (No model.)

To all whom it may concern:

Be it known that I, WILLIAM L. ADAMSON, a citizen of the United States, residing at Philadelphia, in the county of Philadelphia and 5 State of Pennsylvania, have invented certain new and useful Improvements in Means for Stopping Railway-Trains at Danger-Signals, of which the following is a specification.

This invention relates to railway-signals and 10 the combination therewith of means whereby the signals when set to "danger" shall operate connected mechanism to set the air-brakes and stop the locomotive and the train to prevent their passage by the signal in case from 15 any cause the engineer shall fail to observe the signal, and thereby eliminate the risk of rear-end collisions with preceding trains which may have passed the signals and which are running at less speed or which have made a 20 stop within the block.

The invention is illustrated in the accompanying drawings, in which like parts are designated by similar reference characters, and in which—

25 Figure 1 is a side elevation of a portion of a locomotive and a signal. Fig. 2 is a semi-front elevation of a locomotive, the cross-section of the track, and the signal. Fig. 3 is a cross-section of the brake-valve closed as before the operation of the signal. Fig. 4 is a cross-section of the brake-valve open as done by the signal.

The signal-tower 1 may be any of the preferred forms, operated by pneumatic, hydrostatic, or other power which employs a cylinder 2, with a piston 3, operating a rod 4, which raises and lowers the signal 5. Attached to the rod 4 is a gear-rack 6, engaging a pinion 7, secured to the shaft 8, which 35 passes within the track, is secured in a bear-

ing 9, and carries an arm 10, adapted to swing to a vertical position reaching above the rails when the piston moves the rack up, as when the signal is set, and to move to a level position below the rails as the piston 45 moves the rack down when dropping the signal. As seen in Figs. 1, 2, the signal is set or up. The train-pipe 11 of the locomotive has a pipe 12 thereto connected, which carries a brake-valve (shown in detail in Figs. 3, 4) 50 and comprises a case 13, with an opening 14 at one side. Within the case is the valve 15, having a hollow center 16, with a part 17 of its outer surface cut away, so that the passage from pipe 12 to its center is always open; but when the arm 18, which is attached to the valve, abuts the arm 10, as it will do when the signal is set, arm 10 will assume the position shown in Fig. 4, when air will escape through opening 14 and the brakes will be set. An 60 arm 19 of the valve is engaged by spring 20 to hold the valve in its normal closed position.

I claim—

In a train-stopping device, a signal operative by power applied to a piston, a rod from 65 the piston, a rack upon the rod, a pinion engaging the rack and operating a shaft having an arm at its opposite end adapted to move to vertical and horizontal positions, and a valve located in communication with a train-pipe, 70 having means to abut the arm aforesaid when it is placed in a vertical position and thereby open the valve and the train-pipe.

In testimony whereof I affix my signature in presence of two witnesses.

WILLIAM L. ADAMSON.

Witnesses:

RANSOM C. WRIGHT,
WILLIAM C. STOEVER.
